UNITED STATES PATENT OFFICE.

FRANK MURPHY, OF NEW YORK, N. Y., ASSIGNOR OF ONE-HALF TO HENRY ROTEN-BERGER, OF NEW YORK, N. Y.

AUTOMOBILE LICENSE-PLATE HOLDER.

Application filed April 22, 1924. Serial No. 708,114.

To all whom it may concern:

Be it known that I, FRANK MURPHY, a citizen of United States, residing at New York, in the county of New York and State of New York, have invented certain new and useful Improvements in Automobile License-Plate Holders, of which the following is a specification.

This invention relates to improvements in devices for securing sign plates, and more particularly such as are used in connection with vehicles, in an adjusted position.

One of the objects of the device is to positively prevent the unauthorized removal of a license plate sign or its substitution by another.

Another purpose is to produce means for locking a sign in position, so that it may be easily read, the device being in the form of an attachment adapted to be permanently applied to a vehicle.

A further aim is in the provision of means whereby the sign is exposed to the rays of light emanating from an electric lamp bulb, forming part of the attachment.

These and like other objects and aims are attained by the novel construction and combination of parts hereafter described and shown in the accompanying drawing, forming a material part of this disclosure, and in which:—

Figure 1 is a front elevational view of a conventional type of license sign plate as held in engaged position with an embodiment of the invention.

Figure 2 is a longitudinal sectional view of the same, taken on line 2—2 of Figure 1.

Figure 3 is a transverse sectional view taken on line 3—3 of Figure 1.

Figure 4 is a partial front elevational view of the support frame, the sign being shown as unlocked and removed.

Figure 5 is a fragmentary transverse sectional view of a modified form of locking means, through the center of which the view is taken.

It is to be understood from the drawing that the bar, designated by the numeral 10, and its angular elements 11, are rigidly engaged in the usual manner at the rear of a vehicle and are secured to the back of a casing 12 having forwardly extending upper and lower elements 14 and 15 respectively.

The upper element 14 is downturned as at 16 and correspondingly the lower element

15 is upturned as at 17 throughout its entire length. The wedge 16 is turned re-entrantly upward and at the center of the device forms the rear wall 18 of a lamp casing, the same having a domed top 19 and a front wall 20 in which is set a lens 21.

Within the casing is an electric lamp bulb 22 energized by current passing through the wires 23 and entering the casing at the rear. The lamp or lens may be colored, preferably red, and controlled in any of its methods in common vogue, the main rays of the lamp being directed downward through the open bottom of the lamp casing.

Secured on the inner surface of the casing plate 12 are pairs of opposed elongated brackets 23 and 24 and inserted between the raised outer members of the brackets and the elements 16 and 17 is the license sign plate 25.

In order to positively secure the plate 25 and prevent it from being removed, accidentally or otherwise when it has been entered, a plate 26 is secured to the back of the casing plate 12, as by rivets 27, one of the edges of the plate 26 being extended past the end of the frame, shaped and coiled to present a hinge element 28 and carrying a hinge pin 29 by which the other element 30 of the hinge is engaged.

The element 30 is bent at a right angle to form a plate 31 in which are secured the ends of a hasp or U shaped loop 32 adapted to extend through a suitable opening in the sign plate, near its end, and also through an opening 33 in the casing wall 12 and plate 26, so as to be engaged by a lock 34 of the padlock or portable type.

In the modification shown in Figure 5, in place of the hasp 32, a pair of posts 35 are fixed in the hinge plate or leaf 31, the posts having notches 36 near their rounded outer ends and are engageable in a lock 37 which may be of the permutative type as indicated by the dial 38.

In operation, the lock, of whatever type used, is removed, the leaf or hinge plate 31 turned outwardly and the license sign plate 25 pressed into its casing from the end until the openings in the plate, its casing and the stationary hinge leaf are in register, whereupon the leaf 31 is turned down, causing the hasp to pass through the several openings and the lock applied.

From the foregoing it will be seen that a

simple and secure fastening device for a plate sign has been disclosed in the preferred form of its embodiment, but it will be understood that minor changes may be resorted to without departing from the spirit and scope of the claims hereto appended.

Having thus described my invention, what I claim as new and desire to secure by Letters Patent, is:—

- 10 1. A license plate support comprising a casing rigidly attached to a vehicle, slide-ways on the upper and lower edges of said casing, a license plate having an opening near one of its ends, a leaf hinge having one member fixed on said casing, a hasp carried by the other member of said hinge, said hasp being adapted to pass through the openings in said plate and casing, and means for locking said hasp when in an en-gaged position.
- 15 2. A license plate support comprising a casing rigidly attached to a vehicle, slide-ways on the upper and lower edges of said casing, a license plate having an opening near one of its ends, a pair of spaced plates

hingedly connected together, one of said plates being fixed to the back of said casing near one end thereof, a hasp fixed on the inner side of the other plate, said hasp being adapted to pass through said license plate and casing, and means for engaging said hasp to prevent unauthorized retraction.

3. A license plate support comprising a casing rigidly attached to a vehicle, slide-ways on the upper and lower edges of said casing, a license plate having an opening near one of its ends, a leaf hinge having one member fixed on said casing, a hasp carried by the other member of said hinge, said hasp being adapted to pass through the openings in said plate, a lock engageable with said hasp, a lamp casing combined with the sign casing, and a colored lens in the front of said lamp casing, the downwardly disposed light rays from said lamp being di-rected upon said sign plate.

In witness whereof I have affixed my sig-nature.

FRANK MURPHY.
